UNITED STATES PATENT OFFICE.

ROY L. BARTON, OF MILTON, IOWA.

HARROW-WEIGHT-DISTRIBUTING DEVICE.

Application filed November 21, 1925. Serial No. 70,643.

This invention relates broadly to an improved harrow structure, and has more particular reference to an apparatus or device to be used in association therewith for distributing weight.

Ordinarily, where a harrow is composed of a plurality of separate tooth carrying frames, it is comparatively difficult to distribute the weight of the operator on all of the frames. This is due more particularly to the fact that the individual frames travel on different planes owing to the irregularity of the surface traversed.

With the operator or driver usually seated over the central frame, it is obvious how difficult it is to equalize the weight on all frames so that the teeth will be forced sufficiently deep into the surface.

Briefly, I provide a seat which is located over the center of the central frame of the harrow, and support this seat upon an arch, the lower ends of the arms of which are connected with a pair of individual members for transferring the weight of the operator to the end frames and the central frame in an equalized manner even when the two end frames are travelling on irregular surfaces disposing one in a higher plane than the other.

In the accompanying drawings forming a part of this application, and in which like numerals are employed to designate like parts throughout the same:—

Figure 1 is a top plan view of a harrow constructed in accordance with the present invention.

Fig. 2 is a front elevation with the draft appliance removed.

Fig. 3 is an end elevation.

Fig. 4 is a detail view of the seat supporting member,

Fig. 5 is a detail view on an enlarged scale of the seat mounting,

Fig. 6 is a detail view showing the particular manner in which the weight distributing pipes are connected with the central cross bars of the frame.

Fig. 7 is a perspective view of a two-way connector providing a desirable connection of the pipes with said cross bars.

As previously intimated, the structure embodies three harrow frames 1, 2 and 3, the central frame being designated by the character 2 and the two end frames by the characters 1 and 3. All of these frames are of duplicate construction and are provided with

suitable perforating teeth. Extending across the center of the top of each frame is a longitudinal cross bar 4. Fastened to the forward ends of the several frames is a suitable draft appliance or hitching device designated generally by the reference character 5. This is made up of an arrangement of conventional trees.

The weight distributing and equalizing device which is represented generally by the reference character 6, is disposed over the central portion of the harrow frames and extends transversely of the line of draft. This device comprises an arch 7 better shown in Fig. 2. The apex of the arch is disposed centrally over the central frame and downwardly diverging arms are provided at their lower ends with forks 8 which straddle and are pivotally connected to a pair of duplicate pipes 9.

It will be noted that the inner end portions of these two pipes are disposed in somewhat overlapping relation as indicated approximately by dotted lines in Fig. 1. The opposite ends of both pipes are connected to the adjacent cross bars 4. In accomplishing these connections, I employ special two-way connectors 10 such as are shown in Fig. 7. Each connector is made up of pairs of spaced ears 11 and 12 respectively. The ears 12 straddle and are pivotally connected as at 13 (see Fig. 6) to the bars 4. This allows forward and rearward rocking of the pipes 9. The pipes are connected to the right angularly disposed ears 11 by pivot pins 14. In this way a substantial universal joint is had, which is necessary in the proper operation of the structure.

From the description so far given, it is to be seen that the weight distributing structure is partially controlled by a pair of pipes 9 connected at their outer ends to the cross bars 4 on the outer frames and sufficiently connected at their inner ends to the central frame cross bar. There are necessarily two special connectors 10 at the inner ends while there are single connectors at the outer ends. In addition there is an arch which has its lower end forked and pivotally connected to the intermediate portions of the pipes. The apex of this arch is flattened and the horizontal part of a U-shaped member 15 rests on and is connected to this apex.

The operator's seat 16 is adjustably mounted on the horizontal part of this member 15 as more plainly shown in Fig. 5.

Referring to this figure it will be seen that I simply provide a clamp including a cross plate 17 and a retaining bolt 18, the bolt passing through the straight parallel portion of the member 15. The member 15 has the free end portions of its arms extending downwardly at an incline and a strip 19 is fitted between these arms as plainly shown in Fig. 4. This strip is pivotally connected 10 at 20 to the draft appliance and that portion which is confined between the arms of the member 15 is provided with rack teeth 21 through which cross pins 22 extend. This allows a telescoping adjustment of the strip 15. While on this figure, attention is directed to the foot piece 23 which is clamped or otherwise mounted on this depending part of the seat supporting member.

It is clear from the foregoing description that when the operator occupies the seat 16, his weight will be equally distributed by the arch and pipes arranged in the manner specified regardless of the relatively different planes that the harrow frames 25 must occupy in travelling over different elevations of ground. The manner in which this is accomplished is undoubtedly clear

and more lengthy description of the structure is deemed unnecessary.

While the preferred embodiment of the invention has been shown and described, it is to be understood that minor changes coming within the field of invention claimed may be resorted to if desired.

Having thus described my invention, what I claim as new is:—

In a structure of the class described, a plurality of individual harrow frames, a draft appliance connected with the forward ends of said frames, a centrally disposed bar 40 extending longitudinally of each frame, two-way connectors mounted upon the central portions of said bars, a pair of pipes pivotally connected at their opposite ends to said connectors, a vertical arch having the 45 lower ends of its arms pivotally connected with the intermediate portions of said pipes, an extensible connection between the central portion of the arch and said draft appliance, and a seat supported adjacent the central 50 part of said arch.

In testimony whereof I affix my signature.

ROY L. BARTON.
